CAST METAL MODEL RAILROAD TRACK

Wilmer P. Faber, Denver, Colo.

Application August 24, 1946, Serial No. 692,764

1 Claim. (Cl. 238—10)

1 This invention relates to improvements in toy and model railway tracks.

The use of toy railways for the amusement and instruction of children is quite extensive and the building, especially by amateurs, of model railroad trains, is quite a hobby.

Toy railways have come equipped with tracks that are usually pressed from some thin sheet metal and are very cheaply and flimsily constructed.

The ordinary toy railway track, due to its poor and weak construction, is liable to become disarranged so that it will not function properly, and if accidentally stepped on by a child or by an adult, it will be crushed beyond possible repair.

It is the object of this invention to produce a railway track more especially for toy and model railroads which shall be made from cast material, either metal, such as aluminum, or aluminum alloys or of some suitable plastic. The construction of the track is to be such that it will be sufficiently strong to resist breakage, even if stepped on by a grown up person.

Another object of the invention is to produce a cast railway track that can be molded in sections and readily assembled into any lengths and which shall comprise curved sections that can be employed for interconnecting the straight sides of an endless track and which shall be so designed that the curved sections may be used at either end of such track, being reversible, so as to fit either a right or a left hand turn.

A further object of the invention is to produce a railway track of the class described which shall be provided with interconnecting dowel pins arranged in alternate relation by means of which the several sections can be firmly and rigidly interconnected.

A further object of the invention is to produce a railway section that shall have one rail, either one of the rails supporting the cars or a third rail, which is insulated from the railway track and which is so designed and constructed that when the several sections are interconnected, the insulated rail will automatically effect any electric connection.

A further object of the invention is to produce a railway track that shall have the appearance of an actual railway having ties that are clearly visible and which give the effect of a graded railway with either stone or cinder ballast.

The above and any other objects that may become apparent as this description proceeds are attained by means of a construction and an ar-

angement of parts that will now be described in detail, and for this purpose reference will be had to the accompanying drawing in which the invention has been illustrated in its preferred form, and in which:

Figure 1 is a top plan view showing portions of three straight railway sections interconnected in operative relation, portions having been broken away and shown in section so as to better disclose the construction;

Figure 2 is a section taken on line 2—2, Figure 1;

Figure 3 is a section similar to section 2 but instead of showing a third rail insulated from the track, it shows one of the train supporting rails so insulated;

Figure 4 is a section taken on line 4—4, Figure 3, and shows one way in which the electrified rail is supported by and insulated from the base;

Figure 5 is a section taken on lines 5—5, Figure 1;

Figure 6 is a top plan view to a somewhat enlarged scale showing the adjacent ends of two railway sections and shows in greater detail how the electric connection is effected between the ends of the third rail;

Figure 7 is a diagram in the form of a top plan view showing how the curved sections can be used, either for a right or for a left hand turn;

Figure 8 is a section taken on line 8—8, Figure 6.

In the drawing reference numeral 10 designates a supporting surface such as a floor and reference numeral 11 designates the base or road bed part 35 of the invention. It will be observed from Figure 2 that the base is provided with inclined sides 12 whose edges rest on the supporting surface. The center part, which has been designated by reference numeral 13, is elevated above the supporting

40 surface and has formed integral therewith a transversely extending slightly elevated surface 14 that represents ties. Tracks 15 are cast integral with the base and the latter is also provided at the center of some ties with a pair of spaced 45 lugs 16 that position a third rail 17 which is positioned between the lugs and electrically insulated therefrom by some suitable insulating material like that designated by reference numeral 18. The ends of the third rail have been

50 designated by reference numeral 19 and these are slightly bent, as shown most clearly in Figure 6, so that when two sections are interconnected, the ends 19 will come into good electrical contact and will be slightly bent so as to be under sufficient strain to maintain the contact.

Each track section is provided with two dowel pins which have been designated by reference numeral 20, the end of each section has one dowel pin and one opening for the reception of the dowel pin carried by the other section. The dowel pins are secured to their sections by solder or by any other suitable means so as to be permanently attached to the section at points indicated by reference numeral 21. Each dowel pin is provided with a transverse hole 22 which is in register with a corresponding hole in the material of the base and the sections are interconnected with pins 23, as shown more particularly in Figure 5. After the sections have been assembled and interconnected, they form a very substantial and rigid structure that will resist forces that would destroy the ordinary toy railroad track. For the purpose of interconnecting the ends of the straight sections to form an endless track, each set is provided with a number of arcuate sections like those designated by reference numeral 24 in Figure 7. Due to the fact that each end of the curved sections 24, like the ends of the straight sections, is provided with a single dowel pin 20 and an opening positioned to receive a corresponding dowel pin from the adjacent section, the curved end sections may be used to effect either a right or a left hand curve and can, therefore, be employed at either end of a closed track.

It has been pointed out above that some toy trains and model trains are so constructed that a third rail is not necessary, the current being picked up from one of the supporting rails, which is insulated from the base, and returned to the electric source by the other rail and the supporting structure.

In order to accommodate toy and model trains constructed in the manner just described, the track has been slightly modified as shown in Figures 3 and 4. In this construction the third rail has been omitted together with the lug 16 and in the place of the third rail a combined supporting rail and electric conductor like that designated by reference numeral 25 is substituted. This rail has downwardly extending pins 26 at spaced intervals and the ties are provided with openings spaced to correspond with the spacing of the pins and the latter are surrounded by an insulating sleeve 27, which separates the rail 25 from the conducting base. The track sections are provided at their ends with transversely extending flanges 28 as shown in Figure 8 and may also have transversely extending flanges at intermediate positions if desired. The use of these transverse flanges or ribs gives added strength and makes it possible to make the tracks thinner than otherwise.

Particular attention is called to the fact that by using a molded construction, the track can be given the appearance of a cinder or ballasted roadbed as indicated by the stippling in Figure 1.

Particular attention is also called to the manner in which the third rail is insulated. The pins 16 are molded at the time that the remainder of the track is molded and the third rail is merely provided with insulating covering 18 that electrically separates it from the pins 16 and from the upper surface of the ties.

The construction employing the dowel pins alternately arranged makes it possible to positively prevent the sections from coming apart by employing pins 23, which may be easily removed whenever the track has to be separated.

In cases where mechanically operated trains, for example, such as are driven by means of springs or by small gasoline or steam engines, are employed, the third rail may be omitted and can be removed very readily by simply lifting it upwardly from its position between pins 16. Pins 20 are preferably applied after the track has been molded because, by doing so the holes may be correctly positioned by means of suitable templates, whereas, if the pins were to be molded in position it would be more difficult to obtain a satisfactory fit and would require the pins to be considerably smaller than the holes which would result in a lost motion that would permit relative transverse movement of the sections which would be highly objectionable.

Having described the invention what is claimed as new is:

A sectional model railroad track having a section formed of cast metal and a pair of spaced rails cast integral therewith, means at the ends of the section to reversibly join either end thereof to a like section, pairs of upstanding members spaced longitudinally of the section, a third rail arranged between said pairs of members, means for electrically insulating said third rail from said members, said third rail having the ends thereof bent in opposite directions laterally of the longitudinal axis of the section and extending therebeyond, the construction being such that the ends of said third rail will provide electrical contact with adjacent third rails on like sections in reversible positions of assembly, said first named means comprising a dowel pin secured to the section and projecting longitudinally beyond the end thereof at each end of the section, on opposite sides and the same distance from the third rail, an aperture in each end of the section, similarly disposed for receiving a dowel pin, whereby the sections may be reversibly joined, and a transverse pin extending through a portion of the section and a dowel pin to lock a section to a like section.
